TYPEWRITING MACHINE

William F. Helmond, West Hartford, Conn., assignor to Underwood Elliott Fisher Company, New York, N. Y., a corporation of Delaware

Application March 12, 1937, Serial No. 130,537

11 Claims. (Cl. 197—189)

This invention relates to typewriters, and particularly to page-end alarms or signals.

The invention includes a weak but repetitious alarm, such as the blinking of a light in the line of vision, or the tinkling of a bell.

There are employed two page-end alarms, one of which may be actuated at a certain predetermined line above the page-end and the other of which may be actuated at another predetermined line above the page-end, or a signal may be actuated at each line of a predetermined number above the page-end.

One signal may be mounted on the carriage and the other on the front of the typewriter.

One signal may be primary, and the other may be repeatedly operated while typing.

A signal may operate independently and intermittently for an appreciable period.

A light-signal may be given pendulum motion to oscillate a polished, colored or bezel-type signal whereby the signal rapidly changes from a condition of low visibility to high visibility, alternately, the attention-arresting value of the signal being in this manner greatly enhanced. The signal may be actuated by a paper-feeler that drops into a circumferential groove in the platen.

A paper feeler may cause a pinion mounted in the frame to mesh with a carriage-rack, and the pinion may actuate a blinking or intermittent signal.

The signal proper may be a rotatable disk, a part of which is visible through the front-plate of the typewriter, and having sectors of contrasting colors. Or the signal may be a tinkling bell intermittently actuated and having the clapper pivotally mounted and balanced under tension.

Other features and advantages will hereinafter appear.

40 In the accompanying drawings,

Figure 1 is a left side elevation, partly sectioned, showing a disk signal at the right and the operating pinion out of mesh with the carriage-rack, and a carriage signal held inoperative while a sheet of paper is under the paper-feeler.

Figure 2 is a front elevation, parts sectioned and removed, with the signals still inoperative.

Figure 3 is a view of the disk signal with the front plate of the typewriter removed.

50 Figure 4 is a side elevation with parts broken away but including the carriage-rack releasing lever.

Figure 5 is a view similar to Figure 1 showing both paper-feelers in signal-operating position.

55 Figure 6 is a front view of the carriage signal.

Figure 7 shows a paper-sheet on which the locus of the primary signal for a given setting and the locus of the secondary signal are indicated.

Figure 8 shows the lower end of a paper-sheet on which the locus of the primary signal at a setting further from the page-end than in Figure 7, and the locus of the secondary signal are indicated.

Figure 9 shows a carriage-rack operated signal in which a bell is caused to tinkle continually during a line of typing.

An Underwood standard typewriter may have a frame 10 that mounts type-keys 11 on levers mounted on a bracket 12. A front plate 13 is secured by screws 14 to the frame 10. An escape-ment housing 15 supports a carriage-escapement ratchet wheel 16 and pinion 17 on pivot 18. An escapement pawl 19 is shown in Figure 2. A scale-bar 20 and front cross-rods 21 and 22 are shown mounted on the frame 10 in Figure 1. On the rear of the frame 10 is supported a carriage rail 23 on which a carriage 24 is slidably supported by means of depending brackets 25 at the rear. A spring drum 26 is mounted in the frame 10 and winds a tape 27, the free end of which is tied to a screw 28 depending from the carriage bracket 25, to propel the carriage. A case-shift arm 29 is mounted in the typewriter on a rock-shaft 30 and supports a rail 31 at the front. An actuating lever 32 engages the shift-arm 29.

Roller 33 rotatably mounted on a screw 39 on an arm 40, depends from rod 34 mounted in link 35 which is suspended from rod 36 and supported on a side 37 of the platen-carriage, and supports the carriage 24 on the rail 31 and is prevented from jumping the rail 31 by a hook 38 fastened on front of the arm 40 by a screw 41.

Arms 45 support the platen-carriage and are pivoted on the shaft 46 which is mounted on arms 47 on the carriage 24. An inclined paper-table 48 at the rear of the platen-carriage supports a work-sheet 49 and feed-rolls 50, 51, 52 engage the work-sheet 49 and hold it against the surface of a platen 53 which is rotated in the usual manner by a line-space and carriage-return lever 54 rotatably mounted on a post 55 on the left side of the carriage 24, the rear end of lever 54 engaging a line-space plunger 56. A lever 57 pivoted on a screw 58 mounted on the plunger 56 measures the number of line-spaces and a ratchet-wheel 59 is engaged by a pawl 72 (see Fig. 4) and a detent 60 pivoted on a screw 61 mounted in a side 37 of the platen-carriage to hold the platen in any line-spacing adjustment. A spring 55

55

62 returns the line-space plunger 56 to normal position. The platen 53 is rotatably mounted in sides 37 of the platen-carriage on a shaft 63 and is manually adjusted by a knob 64. A type-head 55 swings toward the platen 53 in the direction of the dotted line. A carriage-rack 66 (see Fig. 4) is supported on arms 67 pivoted by screws 68 on the sides of the carriage 24 and is released by depressing finger-pieces 69 adjacent the sides 37 of the platen-carriage. A spring 70 secured to an arm 67 above a screw 68 exerts tension to hold the rack 66 in engagement with the pinion 17. A usual wing guide 71 is mounted adjacent the platen 53 at the printing point. Near the left end of the platen 53 a groove 74 is formed. This groove 74 may be a circumferential recess with perpendicular side walls and having a definite predetermined depth so that the bottom of the recess lies in a circle centered on the axis of the platen 53. Mounted on the inner side wall 37 adjacent the groove 74 of the platen-carriage is a horizontal pivot stud 75 on which is pivoted the rear end of an arm 76, the front end of which is bent at a right angle across the platen 53 and again bent at a right angle to position a paper-feeler 77 over the recess 74. The bottom of the paper-feeler 77 is rounded to present a smooth surface to either a paper work-sheet 49 or the bottom of a recess 74, and has a low-pitch inclined lower edge at the rear, and another inclined lower edge at the front. The lower rear edge provides a cam that is engaged by the top edge of a work-sheet 49 and so as the work-sheet 49 is advanced the paper-feeler 77 is pushed out of the recess against the tension of a spring 78 one end of which is tied to the arm 76 at 79 and the other end of which is looped about a pin 80 projecting inwardly from the adjacent side 37 of the platen-carriage. The other or front inclined bottom edge of the paper-feeler 77 provides for a not too abrupt dropping of the paper-feeler 77 into the groove 74 when a page-end passes the paper-feeler 77. It is obvious that for a certain position of the stud 75 the distance of the paper-feeler 77 from the printing point always remains the same. Provision is made for adjusting this distance by providing a plurality of holes 81 in the side 37 for setting the pin 75 in a plurality of positions so separated from each other that the paper-feeler 77 is moved circumferentially of the platen 53 exactly one or more line-spaces. Auxiliary pins 80 provide anchorage corresponding to the holes 81 for the spring 78 to maintain a uniform tension on the arm 76. A link 82 is pivoted to the forward end of the arm 76 at 83 and has a hook 84 at the upper end by which it is pivoted in an arcuate slot 85 formed in an arm 88, the slot 85 being arcuate with reference to an axis formed by a pin 89 extending inwardly from a side 37 of the platen-carriage on which the arm 88 is pivotally mounted. The arm 88 supports a signal 90 which, in the inoperative position lies flat over a side 37, as shown in Figures 1 and 2, and in the operative position is upright as shown in Figure 5. The signal 90 may be a flat metal piece and may have a colored or light-reflecting front surface formed by polishing which may also show some eye-arresting design such as the image of a hand 91 formed thereon as shown in Figure 6. To the lower end of the arm 88 is fastened the upper end of a light coil spring 92 which is secured on a post 93 mounted on the inner wall of the side 37 of the platen-carriage.

75 Referring to Figure 1, the work-sheet 49 is

holding the paper-feeler 77 out of the recess 74 so that the arm 76 is swung downwardly on its pivot pin 75 to the lowermost position and so the link 82 is moved to the bottom of the arcuate slot 85 and the arm 88 is tilted on the pivot 89 until the signal proper 90 engages and overlies the top of the side 37 in which position it lies flat on and merges with a mask or cover 95, decoratively covering the side 37, and offers practically no obstruction or protuberance, nor in the inoperative position, being practically inconspicuous, does it in any way distract the operator. The condition obtaining in Figure 1 is maintained until the bottom of the work-sheet 49 passes the paper-feeler 77 whereupon the spring 78 pulls the paper-feeler 77 into the recess 74 and simultaneously lifts the arm 76 and the link 82. When the upper end of the link 82 is pushed up into a free position in the slot 85, as shown in Figure 5, the counter-balancing spring 92 and the momentum imparted to the signal 90 thereby cause the signal 90 to swing to position 90A when spring 92 is again tensioned to swing the signal 90 to position 90B. That is, the play of the link 82 in the slot 85 permits the signal 90 to swing back and forth between the two positions 90A and 90B for a considerable interval of time. This vibratory motion of the signal 90 greatly increases the eye-arresting value of the signal in warning the operator of the approach of the page-end a predetermined adjustable number of lines above the page-end. As shown, the pivotal axis of pin 89 is parallel with the axis of the platen 53. The exact counter-balancing of the arm 76 and the link 82 by the spring 78 to hold the paper-feeler 77 on the paper 49 with suitable pressure and the nice counterbalancing of the signal 90 and the spring 92 improve the operative performance of the signal 90. This signal is always started at the end of a line after line-spacing and wig-wags, or vibrates, during carriage-return to the beginning of a line of typing, thereby providing a simple and effective signal.

The foregoing signal 90 may be associated with another page-end signal as an initial or primary page-end signal.

A second paper-feeler 100, triangular, with the corner polished so to protect sheet 49, is mounted over the groove 74 and preferably in a peripheral path offset from that described by the paper-feeler 77. When combined with the latter the paper-feeler 77 gives a primary signal because it is displaced downwardly and rearwardly with reference to the paper-feeler 100 a distance 55 which, as shown in Figure 1, may be equivalent to one line-space, or in other settings of the paper-feeler 77 another number of line-spaces, that is, the paper-feeler 100 may be permanently set to give a last-line signal operative during the 60 last line of typing. Referring also to Figure 2 the paper-feeler 100 projects rearwardly at a right angle to the arm 101 which is mounted on a forwardly extending arm 102 integral with a lever 103 pivoted on a pin 104 projecting inwardly from the inside wall of the carriage-end plate 37. A spring 105, secured to the top of the arm 103 and to a pin 106, tends to lift the arm 103 and concomitantly pull the paper-feeler 100 into the groove 74, if no resistance be offered. The lever 103 however may have at the top a forwardly extending arm 107 which terminates at the front in a downward extension 108, the top of which may be an inclined cam engaged and depressed by a dependency 109 from the line-space 75

plunger 56 as it is pushed rearwards. It is clear therefore that the spring 105 tends to lift the arm 107 up behind the dependency 109 but if the paper-feeler 100 is overlying a work-sheet 49 or the plunger 56 has been pushed rearwardly so that the dependency 109 engages the flat top of the arm 107, the arm 103 can not be actuated.

The arm 103 has a downward extension 110 in the bottom of which is fixed the left end of a rod 112 the right end of which is fastened in an arm 113 pivoted on a screw 114 mounted on the inner wall of the other carriage-end side plate 31 directly opposite the pin 168. A bell-crank 115 is pivoted on a screw 116 mounted on the escapement housing 15 and has an upwardly extended slotted arm 117 which engages both sides of the rod 112 so that in either upper or lower case position when arm 103 swings upwardly or downwardly bell-crank 115 rocks on the pin 116. The rearward part of the bell-crank 115 supports a pinion 118 engageable with the rack 66 and which has a bevel gear 119 engaged with a bevel gear 120 supported on the inner end of a shaft 121 the opposite end of which is supported in the upper end of a bracket 122 mounted on the key-lever bracket 12 to which it is detachably secured by screws 123. Near the left end of the shaft 121 is a bevel gear 124 meshing with a bevel gear 125 mounted on the inner end of a shaft 126 rotatably mounted at the rear in the bracket 122 and at the front in the plate 13. The plate 13 has two apertures 128 and 129 below and above the end of the shaft 126, and fixed on the shaft 126 behind the apertures is a disk 130 the front face of which may bear sectors of contrasting colors as shown in Figure 3. At the rear a weight 131 is secured to the disk 130 so that in the inoperative position the disk 130 takes the position shown in the drawings with a relatively inconspicuous color exposed in the apertures 128, 129.

The modus operandi of the secondary signal is now clear. When the line-space and carriage-return lever 54 is actuated to return the carriage 24 the dependency 109 moves up the cam 108 and over the arm 107 and holds the arm 103 and the paper-feeler 100 against movement, but when the lever 54 is released at the beginning of the last line, the spring 125 moves the paper-feeler 100 into the groove 74 and swings the gear 118 up into mesh with the rack 66 so that the disk 130 rotates and intermittently exposes contrasting colors in the apertures 128, 129 in the front of the typewriter during the letter-space feed of the carriage 24 across the last line of typing. When, however a new work-sheet 49 is inserted on the platen 53, gear 118 is pushed down out of mesh with the rack 66.

Referring to Figure 9, a modification of the last-line intermittent signal is shown in which for the gear 118 is substituted a pinion 135 carried by the rear arm of the bell-crank 115. When the paper-feeler 100 enters the groove 74 pinion 135 meshes with the rack 66 so that during last-line letter-space feed the pinion 135 is rotated. Mounted to rotate with the pinion 135 is a yoke 136 which is engageable with a trip finger 137 pinned at 138 on the upper end of a bell clapper lever 139 which supports a clapper 140 on the lower end near a bell 141. A screw 142 mounted on a bracket 143 in the machine frame 18 pivotally mounts the lever 139. A spring 144 is pinned to the center of the arm 139 at 145, and to a pin 146 which is mounted on the bracket 143. The effect of the spring 144

is to cause a repetitious tinkling of the bell 141 following each time the trip finger 137 is engaged by the yoke 136. The mounting of the trip finger 137 permits the yoke 136, if rotated reversely, to trip the finger 137 against a spring 148 linking the finger 137 and the lever 139 which tends normally to hold the trip 137 in the position shown in Figure 9 in engagement with a pin 149 mounted on the lever 139. The bell 141 is secured by a screw 150 at a suitable place on the frame 10. As shown one of the ends of the yoke 136 alternately engages the trip 137 every six letter-spaces during the last line of typing and resilient counterbalancing of the lever 139 causes the bell 141 to tinkle until the other end of the yoke 136 engages the trip 137, after which the tinkling is repeated, and so forth across the line.

Both the primary and the secondary signals are independent and may be used separately. 20

Variations may be resorted to within the scope of the invention, and portions of the improvements may be used without others.

Having thus described my invention, I claim:

1. In a typewriter, in combination, a frame, a carriage mounted for reciprocatory movement thereon, a platen rotatably mounted on the carriage and over which a paper-sheet is fed, a circumferential groove on the platen, a paper-feeler on the carriage and overlying and held out of the groove while a paper-sheet is thereunder, a spring tending to move said paper-feeler into the groove, a device operable to give a signal mounted on the typewriter frame, a rack depending from the carriage, a pinion for operating said signal device engageable with the rack, and means actuated by the paper-feeler for moving the pinion into mesh with said rack to operate the signal device. 35

2. In a typewriter, in combination, a frame, a carriage mounted for reciprocatory movement thereon, a rotatable platen on the carriage and over which a paper-sheet is passed to receive lines of typing, a rack mounted on the carriage, a device, including a pinion, operable for giving a signal mounted on the typewriter frame, said pinion being engageable with the rack for operating said signal device, sheet-end-sensing means controlled by said paper sheet and mounted on the carriage, and an operative connection enabling said sensing means to engage said pinion with said rack. 50

3. In a typewriter, in combination, a frame, a carriage mounted for reciprocatory movement thereon, a rotatable platen on the carriage and over which a paper-sheet is passed to receive lines of typing, a rack mounted on the carriage, a device, including a pinion, operable for giving a visual intermittent signal mounted on the typewriter frame, said pinion being engageable with the rack for operating said signal-device, sheet-end-sensing means controlled by said paper sheet and mounted on the carriage, and an operative connection enabling said sensing means to engage said pinion with said rack. 60

4. In a typewriter, in combination, a frame, a carriage mounted for reciprocatory movement thereon, a rotatable platen on the carriage and over which a paper-sheet is passed to receive lines of typing, a letter-feed rack depending from the carriage, a rotary disk having sectors of contrasting colors, an element having an aperture past which said sectors are movable, means connectable with the rack for rotating said signal, and means controlled by said paper-sheet for 70

- connecting said connectable means with said rack.
5. In a typewriter, in combination, a frame, a carriage mounted for reciprocatory movement thereon, a platen rotatably mounted on the carriage and over which a paper-sheet is fed, a circumferential groove on the platen, a paper-feeler on the carriage and overlying and held out of the groove while a paper-sheet is thereunder, a spring tending to move said paper-feeler into the groove, a rack depending from the carriage, an element, having an aperture, mounted at the front of the typewriter, a rotary disk having sectors of contrasting colors mounted behind the aperture, shafting for rotating said disk, and a pinion mounted for movement into and out of mesh with the rack, said pinion operating said shafting, and movable by the paper-feeler into and out of meshing position.
10. 6. In a typewriter, in combination, a frame, a carriage mounted for reciprocatory movement thereon, a platen rotatably mounted on the carriage and over which a paper-sheet is fed, a circumferential groove on the platen, a paper-feeler on the carriage and overlying and held out of the groove while a paper-sheet is thereunder, a spring tending to move said paper-feeler into the groove, a rack depending from the carriage, a bell, a clapper for the bell, a pinion mounted for movement into and out of mesh with the rack, an operative connection from said pinion to said clapper, and means enabling the paper-feeler to move said pinion into and out of meshing position.
15. 7. In a typewriter, in combination, a frame, a carriage mounted for reciprocatory movement thereon, a platen rotatably mounted on the carriage and over which a paper-sheet is fed, a circumferential groove on the platen, a paper-feeler on the carriage and overlying and held out of the groove, while a paper-sheet is thereunder, a spring tending to move said paper-feeler into the groove, a rack depending from the carriage, a bell, a clapper for the bell, a spring for counter-balancing said clapper, a pinion mounted for movement into and out of mesh with the rack, an operative connection from said pinion to said clapper, and means enabling the paper-feeler to move said pinion into and out of meshing position.
20. 8. In a typewriter, in combination, a frame, a carriage mounted for reciprocatory movement thereon, a platen rotatably mounted on the carriage and over which a paper-sheet is fed, a line-space carriage-return lever on the carriage, a circumferential groove on the platen, a paper-feeler on the carriage and overlying and held out of the groove while a paper-sheet is thereunder, a spring tending to move said paper-feeler into the groove, a device operable for giving a signal mounted on the typewriter frame, a rack depending from the carriage, a pinion operatively connected to said signal device and movable into and out of mesh with the rack, means controlled by the paper-feeler for moving the pinion into mesh with said rack to operate the signal, and means acting concomitantly with an operation of the line-space carriage-return lever for holding said pinion out of mesh with said rack.
25. 9. In a typewriter, in combination, a frame, a carriage mounted for reciprocatory movement thereon, a platen rotatably and case shiftably mounted on the carriage and over which a paper-sheet is fed, a circumferential groove on the platen, a paper-feeler case shiftable with the platen and overlying and held out of the groove while a paper-sheet is thereunder, a spring tending to move said paper-feeler into the groove, a device operable for giving a signal mounted on the typewriter frame, a rack depending from the carriage, a pinion on the frame operatively connected to said signal device and movable into and out of mesh with the rack, a connection operable by the paper-feeler for moving the pinion into mesh with said rack to operate the signal, said connection being arranged to permit case-shifting of the paper-feeler with the platen.
30. 10. In a typewriter, in combination, a frame, a carriage mounted for reciprocatory movement thereon, a platen rotatably and case shiftably mounted on the carriage and over which a paper-sheet is fed, a circumferential groove on the platen, a paper-feeler case shiftable with the platen and overlying and held out of the groove while a paper-sheet is thereunder, a spring tending to move said paper-feeler into the groove, a device operable for giving a signal mounted on the typewriter frame, a rack depending from the carriage, a pinion on the frame movable into and out of mesh with the rack, and means actuated by the paper-feeler for moving the pinion into mesh with said rack to operate the signal, said means comprising a lever connected to the paper-feeler and case shiftable therewith, and a lever mounted on the frame and operated by said first named lever to move the pinion into and out of mesh with said rack, said levers having a connection permitting relative movements of said levers at the case shifts.
35. 11. In a typewriter, in combination, a frame, a carriage mounted for reciprocatory movement thereon, a platen rotatably mounted on the carriage and over which a paper-sheet is fed, a circumferential groove on the platen, a paper-feeler lever pivoted on the carriage and having a paper-feeling end overlying and held out of the groove while a paper-sheet is thereunder, a spring tending to move the paper-feeler into the groove, a device operable to give a signal mounted on the typewriter frame, a rack depending from the carriage, a pinion engageable with the rack and operatively connected to said signal device, a bell-crank operable for moving the pinion into and out of mesh with said rack, a pivot on the frame on which the bell-crank is pivotally mounted, a slot in an arm of the bell-crank, a cross rod engaging said slot, one end of said rod being connected to an arm of the paper-feeler lever, and an arm pivoted on the carriage and supporting the other end of said cross rod.
